UNITED STATES PATENT OFFICE

JAMES E. VITU, OF CHICAGO, ILLINOIS, ASSIGNOR TO WEIL PUMP CO., OF CHICAGO,
ILLINOIS, A CORPORATION OF ILLINOIS

CENTRIFUGAL PUMP

Application filed August 12, 1929. Serial No. 385,302.

This invention relates to improvements in centrifugal pumps.

In the art of centrifugal pumps, particularly those of the single stage suction type, having a single impeller, one of the sources of greatest difficulty arises because of unbalanced pressure on the impeller, which causes undesirable end thrust and consequent excessive wear of the parts. Further, because of the increased pressure heretofore existing on the rear side of the impellers of said types of pumps, excessive leakage through the bearing and packing also occurs. While attempts have heretofore been made to overcome the difficulties indicated, so far as I am aware, no satisfactory practical solution therefor has heretofore been suggested.

One object of my invention is to provide a centrifugal pump of the single stage suction type wherein the pressure on opposite sides of the impeller will always be substantially perfectly balanced in all conditions of operation, to thereby eliminate undesirable end thrust and hence prolong the life of the pump.

Another object of my invention is to provide a pump of the type indicated in the preceding paragraph so constructed and arranged that there will be no increase in the cost of manufacture thereof.

Other objects of the invention are to provide a pump of the type indicated which will be simple in construction and efficient in operation.

In the drawing forming a part of this specification, Figure 1 is a side elevational view of the improved impeller used in my invention. And Figure 2 is a diametrical sectional view through the casing and impeller, showing my improvements, and corresponding to the line 2-2 of Figure 1.

In carrying out my invention, I use a casing designated generally by the reference character A and an impeller indicated generally by the reference B, the latter being secured to the usual driving shaft C.

The casing A, in its general construction, may be of any suitable form, the one chosen for illustration being of the vertically split type, having an outer member 10 and an inner

member 11. The two members 10 and 11 are flanged as indicated at 12-12 and bolted or otherwise secured together around the periphery of the casing, in a well known manner. As will be understood, the peripheral formation of the casing is of the volute type, so as to provide a peripheral discharge orifice. The member 10 is provided with an intake orifice 13 located centrally and having its center in alignment with the axis of the shaft C. The inner end of the intake orifice 13 is flared toward the impeller, as clearly shown in Figure 2. The member 11 of the casing A, which is on the side opposite the intake side, is preferably provided with a hub 15 in which is journaled the shaft C, suitable packing glands being employed, as customary.

The impeller is mounted on the shaft C in any suitable manner, the construction shown comprising a reduced section 16 on the shaft outward of which is a threaded end 17. The impeller has a hub 18 seated on the reduced section 16 of the shaft and of slightly greater width, the impeller being retained by a nut 19 on the threaded section and the hub being keyed to the shaft C, as indicated at 20.

Referring to the impeller, the same is of that type commonly termed "open impeller" and is of circular form, having a main centrally disposed web 21 and on each side of the web is a series of like lifting or impeller blades or ribs 22-22, four on each side being illustrated in the drawing. Each of the blades 22 is of generally arcuate form and starts at the hub as indicated at 23. A short distance radially outwardly from the hub, each blade is of reduced transverse section, as indicated at 24, and from there on is gradually flared or enlarged, the surfaces being curved on both faces. The blades, as clear from Figure 1, are uniformly spaced and are extended to the periphery of the web.

Adjacent the hub, the impeller B is also provided with a series of openings or apertures 25-25, four apertures being illustrated and each located between two adjacent blades. Each of the openings 25 has its inner edge 26 thereof arranged substantially

tangent to the hub, the remainder of the edge of the opening being constituted by a composite curve, as shown in Figure 1.

Referring more particularly to Figure 2, it will be noted that the vertical portions of the members 10 and 11 of the casing are so spaced that the same are as closely adjacent the surfaces of the blades as possible without actually being in contact. The member 11 of the casing is recessed or cut back at its central portion, as indicated at 27. The recessed or cut back portion 27 is disposed directly opposite the intake orifice 13 and is of an area corresponding to the area of the innermost flared end 14 of the intake orifice.

The recessed or cut back portion 27 provides a supplemental chamber in communication with the main chamber of the casing, as will be apparent, and is of extreme importance in effecting balanced pressures on the two sides of the impeller. In actual practice, the total or combined areas of the apertures 25 will be made such that they will permit the easy and ready passage of at least half the volume of the liquid being handled by the pump, to the back or far side of the impeller. By reason of the auxiliary chamber 27, an increased space is thus provided for the volume of liquid passing through the apertures 25, and thereby sufficient room is obtained to accommodate that portion of the liquid passing through the impeller to insure the same pressure on the back or far side of the impeller as on the intake side of the impeller, in that portion of the chamber immediately adjacent the flared portion 14 of the intake orifice. As will be understood, a certain amount of impedance arises to the passage of the liquid through the apertures of the impeller and were there no increased space behind the impeller to accommodate the liquid passing through the apertures, the pressures on opposite sides would not be alike, and hence there would still remain the undesirable end thrust. By my arrangement of the auxiliary chamber and proportioning of the apertures 25 so as to accommodate at least half of the liquid being handled by the pump, the pressures are balanced and undesirable end thrust thereby either practically eliminated or so minimized as to be negligible. In this connection, it is to be understood that the balancing effect above referred to is obtained under varying conditions of operation; that is, where the liquid may come into the intake orifice under pressure greater than the atmosphere, or less.

Another result that obviously follows, due to the balanced pressures, is that there will be no excessive pressures tending to force the liquid through the bearing, inasmuch as the developed pressures on the back side of the impeller will not exceed those developed on the front or suction side. Because of the low pressures thus developed, the packing need

not be compressed so tightly as heretofore and hence wear on the shaft and leakage are both reduced and the life of the pump increased.

From the preceding description, taken in connection with the drawing, it will be seen that my improvements do not involve any additional cost in the manufacture of the pump and that the maximum efficiency for any size pump may be obtained by suitably proportioning the orifices and auxiliary chambers in accordance with the description outlined.

Although I have herein shown and described what I now consider the preferred manner of carrying out the invention, the same is merely illustrative and I contemplate all changes and modifications that come within the scope of the claim appended hereto.

I claim:

In a single stage centrifugal pump, the combination with a casing having a centrally disposed intake orifice in one side thereof and a peripheral discharge orifice; of an open type impeller having a centrally disposed web and curved impelling blades on opposite sides thereof; and a shaft on which said impeller is mounted, the shaft being rotatably mounted in the casing, said casing, on the side opposite said intake orifice and in alinement therewith, being provided with an auxiliary chamber offset from and in free communication with the main chamber of the casing in which the impeller rotates, the web of the impeller being also provided with a plurality of apertures in its central portion in alinement with said intake orifice and auxiliary chamber, the total area of the web apertures being such, with reference to the intake orifice, as to allow approximately half the volume of liquid to pass freely therethrough when the pump is in operation, said auxiliary chamber providing an increased space for accommodation and change of direction of flow for that portion of the liquid passing through said apertures and which is handled by those blades on the side of the impeller adjacent the auxiliary chamber whereby to produce substantially equalized pressures on the opposite sides of the impeller.

In witness that I claim the foregoing I have hereunto subscribed my name this 29th day of July, 1929.

JAMES E. VITU.
